UNITED STATES PATENT OFFICE.

JOEL STRAHM, OF BERN, KANSAS.

TANK-HEATER.

SPECIFICATION forming part of Letters Patent No. 700,854, dated May 27, 1902.

Application filed May 23, 1901. Serial No. 61,567. (No model.)

To all whom it may concern:

Be it known that I, JOEL STRAHM, a citizen of the United States, residing at Bern, in the county of Nemaha and State of Kansas, have 5 invented certain new and useful Improvements in Tank-Heaters; and I do hereby declare the following to be a full, clear, and exact description of the invention, such as will enable others skilled in the art to which it 10 appertains to make and use the same.

This invention has relation to a heater for water troughs and tanks and for cooking feed for stock, the purpose being the provision of a simple device of this character which can 15 be operated economically and which is of great heating capacity, so as to warm a given amount of water or cook any required quantity of feed in a comparatively short interval of time.

With these objects in view and such others as may result from the specific structural organization of the heater the invention consists of the novel features, details of construction, and combinations of the parts which 25 hereinafter will be more particularly set forth and finally claimed.

In the drawings, forming a part of the application, Figure 1 is a vertical central section of a heater embodying the invention and 30 showing it applied to a trough or tank. Fig. 2 is a perspective view of the heater. Fig. 3 is a perspective view of the ring removably fitted within the body to concentrate the fuel and form the annular combustion and smoke 35 chamber.

Corresponding and like parts are referred to in the following description and indicated in all the views of the drawings by the same reference characters.

In its construction the heater comprises a vertical body 1, a base portion 2, and an outlet-pipe 3, the latter serving to carry off the products of combustion and to insure a circulation of air through the fuel, which is essential to promote combustion thereof. The body 1 and base portion 2 are formed so as to prevent the entrance thereto of water or other liquid, and the body 1 reaches to a height so as to extend above the level of the water 45 or feed in the trough or tank 4, so as to prevent entrance of the same by splashing or otherwise into the heater. The body 1 may

be of any cross-sectional area and outline and is centrally disposed with reference to the base portion 2. In the preferable construction the parts 1 and 2 are of circular outline, as indicated most clearly in Fig. 2. The base portion 2 is of greater diametrical extent than the body portion 1 and is shallow by comparison, and its outer upper portion 55 is constructed to provide an annular chamber 5 into and through which the hot air, smoke, and gases rise and circulate. The outlet-pipe 3 communicates with the annular chamber 5, so as to carry off the hot air and products of combustion. The annular chamber 5 may be formed in any convenient way, and in order that its depth may be regulated it is preferred to provide a ring 6, which is removably fitted within the body 1 and is 60 supported therein by an outer flange *a* at the upper end of the ring engaging with an inner flange *b* at the lower end of the body 1. This ring projects below the top of the base portion 2 and forms the inner wall of the annular chamber 5. This ring can be removed when burned or otherwise disabled for further effective service and can be replaced by a new one. The removability of the ring 6 65 enables it to be substituted by a ring of greater or less height, according to the required depth of the chamber 5. By having the base portion of greater diameter than the body 1 and made shallow the heat is radiated more quickly to the liquid or feed in which 70 the device may be immersed.

The heater may be constructed solely of sheet metal or may be cast or may be partly formed of cast metal and sheet iron or steel, as found most advantageous, according to the 75 size and special use for which the device is designed.

When placed in the trough or tank 4, the heater is secured in place by rods 8, which may be passed through openings in lugs or 80 offstanding portions 9, applied to the base portion 2 or other laterally-projecting parts 10 of the body portion 1. The manner of securing the heater in the trough is immaterial within the scope of the invention and is a 85 matter of minor importance. The outlet-pipe 3 is connected by a brace-piece 11 with the upper end of the body 1, and the latter is closed by a cap 12, having a damper 13, by 90

means of which the draft can be controlled, according as a brisk or slow fire is desired to be maintained in the heater. The central portion of the base 2 constitutes the fuel-chamber and the outer portion the combustion-chamber, which has direct communication with the annular or smoke chamber 5. After the fire has been started the draft is controlled by means of the damper 13, and the smoke and gases rise into the chamber 5 and pass off through the pipe 3. Fuel is supplied through the body 1, and the ashes are removed through the said body by means of a shovel, scoop, or like contrivance.

15 The top 15 of the hollow base 2 has an opening to receive the lower end of the body 1, and a rim 14 surrounds the said opening and encircles the lower end of the body 1, to which it is riveted, bolted, or otherwise firmly attached.

20 Having thus described the invention, what is claimed as new is—

The herein-described tank-heater comprising a shallow hollow base having an opening in its top and a rim extended vertically from the said opening, a hollow body having its lower end fitted within the said rim and secured thereto and formed with an inner flange, a ring removable through the hollow body and having an outer flange at its upper end to rest upon the inner flange at the lower end of the hollow body and hold the ring suspended within the upper portion of the hollow base, an outlet-pipe connected to the top of the base at one side of the hollow body, 35 and a cover fitted to the upper end of the hollow body and having damper-controlled openings, substantially as described.

In testimony whereof I affix my signature in presence of two witnesses.

JOEL STRAHM. [L. S.]
